(57) **CLAIM**

The ornamental design for a bottle for beverages, as shown and described.

DESCRIPTION

Fig. 1.1 is a perspective view;

Fig. 1.2 is a front view;

Fig. 1.3 is a left side view;

Fig. 1.4 is a right side view;

Fig. 1.5 is a rear view;

(Continued)

Fig. 1.6 is a top view;

Fig. 1.7 is a bottom view.

The broken lines in the drawings depict portions of the bottle for beverages that form no part of the claimed design.

1 Claim, 7 Drawing Sheets
